TRUING MECHANISM

Elijah F. Render, Deer Park, Ohio, assignor to
 Cincinnati Grinders Incorporated, Cincinnati,
 Ohio, a corporation of Ohio

Application September 11, 1941, Serial No. 410,449

4 Claims. (Cl. 125—11)

This invention relates to truing mechanisms for grinding machines and the like.

One of the objects of this invention is to provide an improved mechanism for truing the grinding wheels of a duplex grinding machine with a single truing tool.

Another object of this invention is to provide a truing mechanism having quick adjusting means for size changing purposes whereby successive grinding wheels may be trued to different diameters in a single stroke of the truing tool.

A further object of this invention is to provide an improved truing mechanism which is quickly adjustable for truing different compound surfaces on the several grinding wheels of a duplex grinding machine.

Other objects and advantages of the present invention should be readily apparent by reference to the following specification, considered in conjunction with the accompanying drawings forming a part thereof and it is to be understood that any modifications may be made in the exact structural details there shown and described, within the scope of the appended claims, without departing from or exceeding the spirit of the invention.

Referring to the drawings in which like reference numerals indicate like or similar parts:

Figure 1 is a plan view of a duplex grinding machine showing the application of this invention.

Figure 2 is an enlarged plan view partly in section of the truing mechanism.

Figure 3 is a vertical section on the line 3—3 of Figure 2.

In the production manufacture of small parts having two surfaces to be ground it is sometimes the practice to mount two grinding wheels on the same spindle of a plain grinding machine and in such properly spaced relation thereon that by the use of an infeed grinding cycle the two surfaces may be ground simultaneously. Where the surfaces are of different diameters it will be obvious that the grinding wheels must be trued to different diameters and that the differential between these trued diameters must be equal to a high degree of precision to the differential between the desired finish diameters of the work because no relative adjustment can be made between the wheels to correct one work diameter with respect to the other.

In Figure 1 of the drawings there is shown a plain grinding machine which may be of the type shown in United States Patent No. 2,101,644,

issued December 7, 1937, to the spindle of which has been applied a pair of grinding wheels indicated by the reference numerals 10 and 11 thus making the machine a duplex grinding machine.

A work piece, indicated generally by the reference numeral 12, has two surfaces 13 and 14 which are to be ground to different diameters by the infeed grinding method. The surfaces 13 and 14 are cylindrical throughout the major portion of their length but the surface 13 terminates in a fillet 15, while the surface 14 terminates in a fillet 16, and the radii of these fillets are different whereby it should be evident that the entire success of the grinding operation depends upon the accuracy to which the grinding wheels are trued individually and with respect to each other.

It may be well to point out at this time that a grinding machine built in accordance with the patent supra is provided with certain controls, the hand wheel 17 being manually rotatable to effect longitudinal movement of the table 18 upon which are mounted the head and tailstocks 19 and 20 respectively for supporting the work piece for rotation; the infeed control wheel 21 which controls movement of the saddle indicated by the reference numeral 22 upon its guideways 23 whereby the table and work mounted thereon may be moved toward or from the grinding wheel; the start and stop control lever 22' for initiating power reciprocation of the table; and the table reversal control 23' which may be manually operated by the handle 24 or automatically operated by dogs on the table engaging the wings 25 and 26 of control 23'.

Reference may also be had to the patent for the manner in which these controls are operatively connected to the operating mechanism of the machine for effecting the various results enumerated in connection with each.

The truing mechanism constituting this invention is so designed and constructed that it may be permanently applied to the table of the machine as shown in Figure 1, whereby no time need be lost in mounting replaceable devices. Again, it is mounted on the end of the table where it does not interfere with the working area of the machine which must necessarily be clear for quick loading and unloading purposes.

More specifically, the truing mechanism comprises a base plate 27 as shown in Figure 3 which is secured directly upon the table 18 and a sub-support 28 upon which is formed a cir-

cular guideway 29 having a beveled guide surface 30 and a vertical guide surface 31.

The axis of curvature 32 of the circular guideway lies outside of the fixture as indicated in Figure 3, and beyond the truing point 33 of the truing tool 34. The truing tool support 35 is mounted on this guideway and is provided with a beveled surface 36 which is circular in extent for engagement with the guide surface 30.

These parts are held in engagement by a gib 37 which is held in engagement with the surface 31 by set screws such as 38. It is the adjustment of these screws which determines the tightness or looseness of the fit between the opposing guide surfaces. When the proper fit has been obtained a lock nut 39 threaded on the adjusting screw is tightened. The truing tool support 35 also rests upon the flat surfaces 40 and 41 on the sub-support and is held against lifting by the interengaging beveled surfaces 30 and 36 and the gib 42 which is secured to the underside of the support 35 as by bolts 43 and thus in engagement with the guide surface 44 formed on the underside of the support 28.

Oscillating movement of the support 35 about its axis of rotation 32 is effected by a worm and worm gear comprising a worm 44 which is fixed with a shaft 45, and worm wheel teeth 46 which are cut directly in the support 35 and integral therewith. The shaft 45 is supported by bearing blocks 46 and 47 more particularly shown in Figure 2 which are secured to the base 27 by screws 48. A hand wheel 49 is secured to the end of the shaft for effecting manual rotation thereof.

The truing tool 34 is secured in a socket 49 by a set screw 50 of a shiftable plunger 51. A spring 52 is interposed between a shoulder 53 on the plunger and a shoulder 54 on the support 35 for continuously urging the plunger in a direction away from the grinding wheel. The plunger may be moved manually by a handle 55 which is screwed into the plunger, the plunger passing through an elongated slot 56 formed in the support for this purpose. The rear end of the plunger is provided with a follower 57 which is adapted to engage any one of three annular stop discs or cams 58, 59 or 60 which are integrally secured to a shiftable support 61. The support has an elongated journal 62 which rides in a bearing 63 formed in the support 35, and is guided at the other end in a bearing 64. A control knob 65 is utilized for shifting the support to any one of three positions to align any one of the three stop members 58, 59 or 60 with the follower 57. To assist in positioning the support it is provided with a series of properly spaced V-notches 66 which are engageable by a spring pressed ball 67 to hold it in any one of its three positions.

To guide the operator in using the mechanism and to indicate when the axis of the plunger 51 is perpendicular to the axis of the grinding wheels the support 35 is provided with a laterally extending pin 68 which is engageable with a stop pin 69 carried by the fixed support 27 and this serves to limit the counterclockwise rotation of the truing tool support and to align it perpendicular to the axis of the grinding wheels.

In the operation of the device the saddle is retracted and the table shifted to the left as viewed in Figure 1 until the truing tool is to the left of the grinding wheel 16. With the follower 57 in engagement with the stop 58 the saddle is adjusted until the truing tool is in alignment with the face of the wheel whereby the table may

be traversed toward the right to true the cylindrical surface 70 shown in Figure 2 of the wheel 16. As previously mentioned, there is a difference in diameter between the grinding wheels and in the case illustrated the grinding wheel 16 is smaller in diameter than the grinding wheel 11. The stop 59 is, therefore, made smaller in diameter than the stop 58 so that the differential in the diameters of the stops is equal to the differential desired between the diameters of the grinding wheels.

The table may be traversed by power to true the wheel 16 through operation of the control 22, or it may be shifted by hand through operation 15 of the hand wheel 17. In any case, as soon as the truing tool passes out of engagement with the wheel 16, the plunger 51 is shifted slightly to take the pressure off of the stop 58 and the stop support 61 shifted one station so that upon release of the handle 55 the follower will engage 20 the stop 59 to position the truing tool to true the diameter of wheel 11 in proper differential relation to the diameter of the wheel 16. With a reasonable rate of power feed this adjustment 25 may be made quickly and the parts properly adjusted to their new position before the truing tool reaches the grinding wheel 11. Thus, the mechanism serves as a quick adjusting mechanism for changing the truing radius of the truing tool.

If it is necessary to make more than one pass of the diamond across the faces of the wheels the 30 table may be reversed and the saddle support adjusted micrometrically by the wheel 21 which is equipped to make such adjustment and after the 35 tool passes out of engagement with the wheel 11 it may be quickly adjusted and positioned by the stop 58 by the time the truing tool reaches the grinding wheel 10. Thus, two different diameters may be trued with the same ease and quickness that a single diameter is trued.

As previously mentioned, the work piece has two fillets 15 and 16 which are of different radius. The grinding wheel 11 must, therefore, be provided with a curved surface 71 for grinding the fillet 15 and the grinding wheel 10 must be provided with a curved surface 72 for grinding the fillet 16. These fillets being of different diameter they cannot be trued with the same set-up but the mechanism of this invention provides 45 means whereby quick adjustment may be made for accommodating both radii. It is accomplished in this manner. When the follower 57 is in engagement with the stop 58 the point of the truing tool is spaced from the axis of rotation 32 of the fixture a distance equal to the radius of the surface 72.

Therefore, when the follower 57 is in engagement with the stop 58, the fixture may be rotated by means of the hand wheel 49 to obtain the radius 72. In other words, the same stop can be used for straight truing and for truing one radius of one of the grinding wheels because for straight truing it is immaterial what the spacing is between the diamond point and the axis 55 of rotation of the truing tool support.

To form the radius 71 the additional stop 60 is provided and this is made smaller than the stop 58 by an amount equal to the difference between the radius of the surface 71 and the radius of the surface 72.

It is, of course, desirable that the straight and curved surfaces of the wheel be trued in one continuous stroke of the truing tool so that on lines are left on the wheel to mar the finished surface 75 of the work. This is accomplished in connection

with the wheel 11 by setting the follower in contact with the stop 60 and relatively shifting the parts to position the truing tool in line with the right hand face of the wheel 11 and then relatively adjusting the supports by the hand wheel 21 until the truing tool is just barely in contact with the face of the wheel. The table is then traversed by hand through manual rotation of the hand wheel 17, and at the point of tangency between the curve and straight surfaces rotation of the hand wheel 17 is stopped and rotation of the hand wheel 49 begun, in such manner that no stoppage in the movement of the truing tool occurs whereby the straight and curved surfaces will be trued in one continuous movement of the truing tool.

In order to indicate to the operator where this point of tangency occurs as indicator plate 73 is attached to the sub-support 28, as shown in Figure 2, by means of clamping bolts 74 which pass through elongated slots 75 in the plate 73. This plate is provided with two marks 76 and 77 which cooperate with a pointer 78 which is fixed to the saddle 22. As the table is traversed by the hand wheel 17 the mark 77 will approach the pointer 78 and the operator effects the changeover when the pointer and the mark are in alignment.

After the wheel 11 has been trued the operator shifts the follower 57 into engagement with the stop 58 and aligns the truing point with the right hand face of wheel 10 and repeats the operation of traversing the table by the hand wheel 17 but this time the changeover is effected when the pointer 78 is in alignment with the mark 76.

Since the grinding wheels 10 and 11 are dished wheels as shown in Figure 2 the point of tangency between the curved surfaces and the straight surfaces will gradually shift toward the right as the wheels wear down. In order to compensate for this the plate 73 is provided with the elongated slots 75 whereby the plate may be gradually shifted toward the right and reclamped at various times through the life of the wheels. After the wheel 10 has been trued by continuous movement of the truing tool in a left hand direction across the face of the wheel, the operation may be reversed by effecting the rotation first and the longitudinal movement second in a continuous manner and then after passing out of engagement with the wheel 10 the truing tool may be reset in engagement with the stop 59 and traversed once across the straight portion of the wheel 11 to insure that the diameters of the wheels are in proper relation. This may be done without leaving any lines on the wheel 11 and insures that the cylindrical surfaces on the work which are the important surfaces are produced with the desired precision relationship.

There has thus been produced a very simple and compact truing mechanism which will perform varied and complicated truing operations in an efficient manner and which any normally skilled operator will not experience difficulty in learning to operate.

What is claimed is:

1. A truing device for application to a grinding machine having a base portion adapted to be secured to the table of the machine, said base having an upstanding arcuate guide portion, a second support member mounted on the first having arcuate ways intervening with the guide portion of the first support whereby the parts are connected for relative oscillatory movement, said supplemental support having passages formed therein angularly related with respect to each

other, a truing tool holder slidably mounted in one of said passages, a control shaft slidably mounted in the other of said passages, a plurality of stop means mounted on said control shaft, an abutment on the tool holder projectable in the direction of the shaft for engagement with a stop element thereon, and means for variably securing the shaft in selectively adjusted positions whereby to align different of the stop means thereon with the abutment on the tool holder, substantially as and for the purpose described.

2. A truing device for application to a grinding machine having a base portion adapted to be secured to the table of the machine, said base having an upstanding arcuate guide portion, a second support member mounted on the first having arcuate ways intervening with the guide portion of the first support whereby the parts are connected for relative oscillatory movement, said supplemental support having passages formed therein angularly related with respect to each other, a truing tool holder slidably mounted in one of said passages, a control shaft slidably mounted in the other of said passages, a plurality of stop means mounted on said control shaft, an abutment on the tool holder projectable in the direction of the shaft for engagement with a stop element thereon, means for variably securing the shaft in selectively adjusted positions whereby to align different of the stop means thereon with the abutment on the tool holder, and means for continuously urging the tool holder into retracted position to maintain the abutment in engagement with a selected stop means.

3. A truing device for application to a grinding machine having a base portion adapted to be secured to the table of the machine, said base having an upstanding arcuate guide portion, a second support member mounted on the first having arcuate ways intervening with the guide portion of the first support whereby the parts are connected for relative oscillatory movement, said supplemental support having passages formed therein angularly related with respect to each other, a truing tool holder slidably mounted in one of said passages, a control shaft slidably mounted in the other of said passages, a plurality of stop means mounted on said control shaft, an abutment on the tool holder projectable in the direction of the shaft for engagement with a stop element thereon, means for variably securing the shaft in selectively adjusted positions whereby to align different of the stop means thereon with the abutment on the tool holder, means for continuously urging the tool holder into retracted position to maintain the abutment in engagement with a selected stop means, the supplemental support having a slot formed therein communicating with the tool holder receiving passage, and actuating means exteriorly disposed as respects the supplemental support engaging the tool holder by way of the slot whereby the interengagement of said means with the sides of the slot secures the tool holder against rotative movement while the projecting portion is actuatable for projection of the tool holder in a direction away from the stop means.

4. A truing mechanism for application to a grinding machine table or the like including a base element securable to the table, said base having an upstanding arcuate portion providing a segmental guideway, a supplemental support portion mounted on the base portion having interfitting engagement with the segmental way on the base, said supplemental support having

a worm rack formed thereon adjacent the way, bracket portions rising from the base, a shaft journaled in said bracket portions having a central worm meshing with the worm rack on the supplemental support whereby the worm normally locks the supplemental support against angular movement relative to the base but may be rotated to effect such movement of the parts, said supplemental support having a transverse guide passage formed therein extending in a radial direction as respects the arcuate path, a truing tool holder slidably mounted within said passage, means for urging said tool holder in a circumferentially outward direction, said supplemental support having transverse bearing passages formed therein lying in substantially a common plane with the axis of the tool holder passage, a shaft journaled in said bearing pas-

sages and having a portion in intersecting relation with the outward potential path of movement of the tool, a multiple number of different dimension stop elements carried by the shaft and selectively positionable in alignment with the tool variably to limit the outward movement thereof for determination of the position of the tool during rectilinear movement of the device and of the radius of arc generatable by the tool on arcuate movement of the supplemental support, means for shifting the tool support in a direction away from the shaft to facilitate shifting of the shaft and stop elements carried thereby, and means for variably positioning the shaft selectively to align individual stop elements with the tool holder substantially as and for the purpose described.

ELIJAH F. RENDER.
